J. OLIPHANT

DISPLACEMENT PUMPING SYSTEM

Filed July 6, 1923

Inventor:
John Oliphant.

Brace G. C.

attorney.

UNITED STATES PATENT OFFICE.

JOHN OLIPHANT, OF CHICAGO, ILLINOIS, ASSIGNOR TO SULLIVAN MACHINERY COMPANY, A CORPORATION OF MASSACHUSETTS.

DISPLACEMENT PUMPING SYSTEM.

Application filed July 6, 1923. Serial No. 649,925.

My invention relates to displacement pumping systems, and more particularly to displacement systems which are especially adapted to deep well pumping.

5 An object of my invention is to provide an improved pumping mechanism. Another object of my invention is to provide an improved displacement pumping mechanism. A further object of my invention is to provide 10 an improved displacement pumping system in which a plurality of displacement tanks are employed and in which the necessity for the use of special air controlling means to effect the proper distribution of air to the 15 various tanks is avoided. In displacement pumping systems in which two series of alternately arranged displacement tanks are disposed in a well and so connected that the tanks of one series fill while those of the other series discharge, it is found that in wells 20 of any considerable depth the reduction in pressure in the fluid supply lines leading to the tanks toward the bottom of the well is so substantial that some kind of controlling 25 means must be used in connection with some of the tanks in order to insure the complete filling and emptying of the tanks at or near the bottom of the well. It will be evident that as air is led off from the supply lines 30 at various points between the top and the bottom the pressure at the bottom will naturally be less than that at the top and, moreover, there will be a loss due to the length of the pipe line. Accordingly, in the 35 tanks towards the bottom the pressure acting may be very much less than that in the tanks at the top and, with a fixed period of fluid admission to the various tanks, it will be evident that, other things being the same, 40 less fluid will be displaced from the lower tanks than from the upper ones. As a result, the system will tend to empty itself and other difficulties will be experienced. To overcome this, it has been customary either 45 to use some kind of fluid controlling means with some of the tanks or to use adjustable throttles so that the rate of admission through the supply line branches to the higher tanks would be reduced by throttling while that of the lower tanks would be either throttled to a less degree or not at all as might be found desirable in practice. I have found however, that these expedients 50 may be avoided by the proper spacing of the tanks and a further object of my invention is

to provide an improved system in which by the proper spacing of the tanks a piping mechanism of the utmost simplicity may be used. Other objects and advantages of my invention will hereinafter more fully appear. 60

In the accompanying drawings, I have shown for purposes of illustration one form which my invention may assume in practice.

The figure is a diagrammatic view of a 65 pumping system constructed in accordance with the illustrative form of my invention.

In the illustrative embodiment of my invention a compressor, whose cylinder is shown at 1, supplies pressure through a line 70 2 to a distributing valve mechanism 3 which is herein shown in elevation and is the invention of one David H. Hunter. This distributing mechanism comprises means for alternately admitting, for periods of substantial duration, air or other pumping fluid to one or the other of two supply lines 5 and 6, this mechanism also serving to connect, while one of these lines is connected to the supply, the other to exhaust or to the 80 suction side of the compressor, (herein the latter). The lines 5 and 6 are the fluid supply lines for the pumping medium supplied to the displacement tanks in the pumping system which I shall now more specifically 85 describe.

Arranged within a well 10 is a casing member 11 which extends from the top of the well down below the level of the water in the bottom of the well. Arranged within 90 this casing is a series of displacement tanks, these tanks being arranged in fact in a pair of series, the tanks of the two series being arranged in alternation. The tanks of one of these series are numbered respectively 12, 95 14 and 16, while those of the other are numbered 13, 15, and 17. It will, of course, be understood that more than six tanks could be employed if desired and that the number of tanks employed will depend upon the air 100 pressure available and the height to which the fluid must be elevated. Check valve controlled discharge connections 19 connect the bottom of each tank with the tank above it, but as this mechanism is well understood, no 105 illustration is thought to be necessary herein other than the dotted disclosure shown. The pipe line 5 extends down nearly to the bottom of the well and is connected by branches 20, 21 and 22 to the tanks 13, 15, 110 17.

and 17; respectively. The pipe line 6 does not extend so far down in the well, but is connected by branches 23, 24 and 25 to the tops of tanks 12, 14 and 16, respectively. 5 From this arrangement it will be apparent that when air is supplied to the line 5 while line 6 is connected either to exhaust or to the suction side of the compressor, tanks 13, 10 15 and 17 will discharge the liquid contained in them to tanks 12, 14 and 16, respectively, while when line 5 is connected to exhaust or 15 the suction side of the compressor and line 6 is connected to the compressor discharge, tank 12 will discharge to any desired point 20 of delivery while tanks 14 and 16 are respectively discharging to tanks 13 and 15, and tank 17 is being filled again due to its submergence. Instead of employing throttle 25 means in the connections 20 to 25, I have found that it is possible by suitably locating the tanks 12 to 17 in the well to avoid any 30 difficulty due to the more rapid pumping of the higher tanks and accordingly, I space the bottom of the tank 12 a maximum distance 35 from the discharge line, space the bottom of the tank 13 a lesser distance from the top of the tank 12, and the succeeding tanks progressively closer together so that the distance from the bottom of the tank 17 to the top of the tank 16 is the least distance of all. For purposes of simplicity I have referred 40 to the distances in terms of from the bottom of one tank to the top of the next tank, but in fact the distances should be considered in terms of from the bottom of the discharge 45 line in a given tank to the maximum water level in the tank next above. It will be evident that as the distance which the liquid must be raised is greatest at the top of the well and is made proportionally less as the 50 pressure drops due to the distance from the compressor and reduction due to withdrawal of air from the line, it will be possible for all the tanks to be emptied substantially simultaneously and for a uniform pumping period to serve for the filling and discharging of the various tanks, although they are 55 spaced by materially different distances from the top of the well. This, in brief, is the gist of the invention: that the tanks be so disposed relative to each other that the reduction in pressure toward the bottom of the well will be offset by the reduction in height to which the liquid must be raised by the successive tanks.

While I have in this application specifically described one form which my invention may assume in practice, it will be understood that this form of the same is shown for purposes of illustration and that the invention may be modified and embodied in various other forms without departing from its spirit or the scope of the appended claims.

What I claim as new and desire to secure 60 by Letters Patent is:

1. In a pumping system, a plurality of displacement tanks arranged in series in a well, and means comprising fluid supply lines connected to said tanks in alternation for alternately supplying fluid pressure to said tanks, said tanks being spaced progressively diminishing distances from each other toward the bottom of the well.

2. In a displacement pumping system, two series of tanks arranged with their tanks in alternation, and means for supplying pressure fluid to all the tanks of one series while venting the tanks of the other series and vice versa, said tanks being so arranged that the head against which any tank must discharge is proportional to the air pressure supplied thereto.

3. In a displacement pumping system, a plurality of displacement tanks arranged in series in a well, the distances between said tanks diminishing toward the bottom of the well, and means for conducting pumping fluid to said tanks.

4. In a displacement pumping system, a plurality of displacement tanks arranged in series in a well, and pumping fluid supply means in said well connected with said tanks, said tanks each having a check valve controlled discharge line leading therefrom, and said tanks being so disposed in said well that the distance from the bottom of any such discharge line to the highest level to which it must discharge is proportional to the pressure of the pumping fluid at its respective tanks.

5. In a pumping system, a plurality of serially arranged displacement tanks, means for supplying actuating fluid thereto from a point remote from the lowermost tank, and means including a plurality of elements having a predetermined fixed relation whereby the time necessary for the substantially complete discharge from each of a plurality of said tanks will be substantially equal.

6. In a pumping system, a plurality of tanks, a common fluid conducting passage communicating freely with each of said tanks, and fixed means adapted to compensate for the drop in pressure in said supply line due to each tank successively drawing its supply of fluid therefrom and thereby insuring a substantially uniform operation of said tanks.

7. In a pumping system, a plurality of tanks, a common supply pipe therefor, said tanks successively drawing their supplies of actuating fluid from said pipe, and a plurality of liquid conducting means of different lengths and arranged with respect to said tanks to overcome the drop in pressure in said supply line to thereby insure substantially uniform operation of said tanks.

8. In a pumping system, a plurality of superimposed displacement tanks adapted to be arranged within a well, means whereby

actuating fluid is freely admitted to each of said tanks under a different pressure, and means compensating for said different pressures to insure that similar operations of 5 said tanks will be substantially uniform.

9. In a pumping system, a plurality of displacement tanks adapted to be arranged in a well, means for freely supplying actuating fluid to each of the same under different pressures, and means whereby certain like liquid content changes in said tanks are 10 made substantially uniform.

10. In a pumping system, a plurality of superimposed displacement tanks, a single 15 source of actuating fluid therefor, means whereby the actuating fluid is admitted to each of said tanks at a different pressure

than at said source to thereby insure that certain similar operations of said tanks will be substantially uniform, the uppermost 20 tank freely receiving substantially full initial pressure.

11. In a pumping system, a plurality of superimposed displacement tanks, a single source of actuating fluid therefor, means 25 whereby the actuating fluid is admitted to each of said tanks at a different pressure than at said source, and means including liquid conducting elements of different lengths to thereby insure that certain similar 30 operations of said tanks will be substantially uniform.

In testimony whereof I affix my signature.
JOHN OLIPHANT.
